Primary Examiner — Jennifer L Watkins*Assistant Examiner* — Bryan C Gusman(74) *Attorney, Agent, or Firm* — Cheng-Ju Chiang(57) **CLAIM**

The ornamental design for a table, as shown and described.

DESCRIPTION

FIG. 1 is a front, top and left perspective view of a table in accordance with my present invention;

FIG. 2 is a front elevational view of the table of FIG. 1;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines in the drawings show portions of the table that form no part of the claimed design.

The table is shown with a symbolic break in its length. The appearance of any portion of the table between the break lines forms no part of the claimed design.

1 Claim, 7 Drawing Sheets(56)
